(57) **CLAIM**

The ornamental design for a head for a golf club, as shown and described.

DESCRIPTION

FIG. 1 is a first perspective view of a head for a golf club showing my new design;

FIG. 2 is a second perspective view thereof;

FIG. 3 is a front view thereof;

FIG. 4 is a left side view thereof;

FIG. 5 is a right side view thereof;

FIG. 6 is a top view thereof;

FIG. 7 is an elevational view taken along line 7-7 end in FIG. 3 thereof; and,

FIG. 8 is an elevational view taken along line 8-8 end in FIG. 3 thereof.

The dash-dash broken lines in FIGS. 1-6 depict portions of the head for a golf club that form no part of the claimed design. The dot-dash broken lines in FIGS. 1-6 define the bounds of the claimed design and form no part thereof. The broken lines shown in FIGS. 7 and 8 are for the purpose of illustrating subject matter that forms no part of the claimed design.
